UNITED STATES PATENT OFFICE

WILBERT D. HENDERSON, OF SAN FRANCISCO, CALIFORNIA

PARTITION-STUD CLAMP

Application filed August 22, 1928. Serial No. 301,361.

My invention relates to improvements in partition-stud clamps wherein a clamping member, shaped to engage the inner surfaces and adjacent sides of a pair of parallel spaced channels arranged to support a partition structure, operates in conjunction with improved means for moving and holding said clamp permanently into gripping arrangement with said channels.

10 The primary object of the present invention is to provide a new and improved partition-stud clamp.

Another object of the present invention is to provide a new and improved construction 15 for a device of the character described in United States Patent No. 1,167,899; issued to me on the 11th day of January, 1916, reference to which patent is hereby made.

A further object of the present invention is 20 to provide a more economical device of greater efficiency than the device disclosed in the patent above referred to.

A still further object is to provide a new and improved device of the class described 25 having a spring tension and arranged to grip instead of merely engage the inner surfaces of a pair of parallel spaced channels, and to hold said members firmly in said spaced relation.

30 I accomplish these and other objects by means of the improved device disclosed in the drawings forming a part of the present application wherein like characters of reference are used to designate similar parts throughout the specifications and drawings, and in which—

Fig. 1 is a broken front elevation of a pair of spaced parallel channels disclosing a pair of my clamps applied thereto;

40 Fig. 2 is a broken side elevation of Fig. 1 with the lower clamp shown in vertical section midway between the channels;

Fig. 3 is a back elevation of Fig. 1;

Fig. 4 is a transverse sectional view of a 45 pair of channels and a clamp, disclosing the said clamp being partly applied;

Fig. 5 is a similar view showing the clamp completely applied; and

Fig. 6 is a sectional view of the clamp before application to the channels, disclosing

the channels in dotted lines for comparative purposes.

Referring to the drawings the numeral 1 is used to designate a pair of channels arranged in spaced parallel relation to each other and comprising the usual webs and legs to form the inner surfaces 3 and adjacent sides 4. A spring clamp member 6 comprises a central or intermediate portion 7 having a centrally located struck-up apertured lug 8 and transversely arranged indented beads 9 adjacent the upper and lower edges of said central or intermediate portion 7 to impart rigidity to said central portion, the purpose of which will hereinafter be more fully set forth.

The intermediate portion connects two outer portions, each comprising laterally extending converging portions 11 formed by bending those portions of the clamps upon themselves to form converging spring portions arranged at a slightly less degree of convergency than that of the adjacent channel-legs which they grip and engage, said converging spring portions being also slightly longer, on their inner or adjacent surfaces, than the corresponding surfaces on the channels, by means of which arrangement said members, being shaped to engage said inner surfaces of said legs and the outer surfaces of said legs, or adjacent surfaces of said parallel channels, may firmly grip said legs when moved thereonto before the inner end of said converging members or portions 11 engage the outer edge or end of said legs, in a manner hereinafter more fully set forth.

Formed beyond these converging portions 11 I have provided further extensions 12 which extensions 12 are formed at an angle to the central or intermediate portion 7, as disclosed in Fig. 6 of the drawings, whereby said extensions 12 will grip and press against said inner surfaces of the channels 1 with a spring tension when the clamp is applied.

In operation a suitable bolt 14 such as a nail of the proper size, and strength, is inserted through the lug 8, as disclosed in Fig. 4 of the drawings. When inserting this bolt one side of the clamp will first be forced or drawn into clamping arrangement with

one of the channels 1 as disclosed in the left hand side of Fig. 4, which will place said bolt or nail 14 in the position shown in said Fig. 4, in which it is shown that the resulting re-
5 action has prevented the other portion of the clamp from moving into gripping ar-
rangement or relation with the remaining channel 1.

The beveled point 16 of the bolt or nail
10 14 will now ride over the inner back corner or edge of the remaining channel, and by means of a hammer or other suitable tool, the bolt 14 may be driven to slide over the back of the remaining channel 1 and there-
15 by move the entire clamp into gripping re-
lation with the channels 1, the intermediate portion 7 serving to hold the channels 1 rigidly in spaced parallel relation and to cause the clamp to firmly and rigidly grip,
20 instead of merely engage, the inner surfaces and adjacent sides of said channels 1.

It is quite obvious that by placing these clamps at regular spaced intervals along a pair of spaced channels that said channels
25 will be firmly gripped and rigidly held in parallel spaced relation to each other and thereby provide a rigid support for a partition or similar structure.

Having thus described my invention what
30 I claim as new and desire to secure by Letters Patent is—

1. A clamp for partition studding members comprising a spring metal strip shaped to engage and hold a pair of structural iron channel members in spaced parallel relation, said strip comprising a central body portion, a pair of channel engaging portions formed at the ends of the body portion to engage adjacent legs of the channel members, the sides
35 of each channel engaging portion being in-
clined relatively to each other at an angle slightly less than the angle between the inner and outer faces of the channel leg, and end portions extending laterally from the channel engaging portions and inclined toward the plane of the body portion to engage the inner surfaces of the backs of the channels; and an outwardly disposed apertured lug struck from the body portion to receive a se-
40 curing member inserted through the aperture of the lug and engaging the backs of the channels to spring the channel engaging portions into gripping engagement with the legs of the channels and compress the end portions against the inner surfaces of the channel backs to exert a spring pressure against said channels.

2. A clamp for partition studding members comprising a spring metal strip shaped to engage and hold a pair of structural iron channel members in spaced parallel relation, said strip comprising a central body portion, a pair of channel engaging portions formed at the ends of the body portion to engage adjacent legs of the channel members, the sides

of each channel engaging portion being in-
clined relatively to each other at an angle slightly less than the angle between the inner and outer faces of the channel leg, and end portions extending laterally from the channel engaging portions and inclined to-
70 ward the plane of the body portion to engage the inner surfaces of the backs of the chan-
nels; an outwardly disposed apertured lug struck from the body portion to receive a 75 securing member inserted through the aper-
ture of the lug and engaging the backs of the channels to spring the channel engaging portions into gripping engagement with the legs of the channels and compress the end por-
80 tions against the inner surfaces of the chan-
nel backs to exert a spring pressure against said channels; and beads formed upon the body portion and extending laterally be-
85 tween the channel engaging portions to im-
part rigidity to said body portion.

In witness whereof, I hereunto set my sig-
nature.

WILBERT D. HENDERSON.
